UNITED STATES PATENT OFFICE.

PAUL EWALD, OF CLINTONVILLE, WISCONSIN.

DRAFT ADJUSTMENT.

1,167,684.

Specification of Letters Patent.

Patented Jan. 11, 1916.

Original application filed August 10, 1911, Serial No. 643,280. Divided and this application filed July 16, 1914. Serial No. 851,344.

To all whom it may concern:

Be it known that I, PAUL EWALD, a citizen of the United States, residing at Clintonville, in the county of Waupaca and State 5 of Wisconsin, have invented certain new and useful Improvements in Draft Adjustment, of which the following is a specification.

This invention relates to an improved draft adjustment for sulky plows and more 10 particularly to a plow of the type which is especially adapted to be used at different angles, that is in plowing rough and uneven ground and this application is a division of the applicant's former application filed 15 August 10th, 1911, Serial No. 643,280.

An object of this invention is to provide a means for adjusting the draft members of the vehicle to conform with the adjustment 20 of the body portion thereof, consequently 20 obviating the unusual position of the tongue when the vehicle is in an adjusted position.

With the above and other objects in view, this invention resides in the novel features 25 of construction, formations, combinations and arrangements of parts to be hereinafter more fully described and illustrated in the accompanying drawings, in which:

Figure 1, is a side elevation of my draft adjustment applied to a sulky plow, Fig. 2, 30 is a top plan view of the same, Fig. 3, is a detail view of the draft operating mechanism, and Fig. 4, is a longitudinal sectional view taken on line 4-4 of Fig. 2.

Referring to the accompanying drawings 35 by similar characters of reference, the numeral 1 designates the body portion or supporting structure of a sulky plow, which as shown in the drawings, is substantially U-shaped. A portion of this frame, is bent to form parallel extensions 2, which extensions provide an auxiliary supporting device for 40 my draft operating mechanism above-mentioned. For the purpose hereinafter set forth, the rear extremity of one of the ends 45 of the body portion is bent at right angles thereto as shown at 3, and again at 4, to form a circular supporting device, the end of which is secured to the body portion by such means as shown at 5. As is readily 50 obvious by reference to the drawings, I have mounted upon this last mentioned supporting structure, the lower extremity of a leaf spring 6, the upper extremity of which carries the ordinary operator's seat 7.

Revolutely supported upon the body por-

tion 1, through the medium of a bearing 8, is an axle 9, the latter being journaled through an extension 10 carried upon an ordinary segmental rack 11, the latter being fastened upon the supporting structure 3, as 60 shown at 12. Further the end of the axle 9 is bent as shown at 12' to form a crank 13. The latter serves as a suitable supporting stud which is received by the hub 14 of the wheel 15. For the purpose of preventing the wheel from running off of the stud, and consequently injuring the operating parts of the device, I have provided a bearing 16, which is secured together as shown at 17. 70

It is now readily apparent that the movement of the axle will adjust the wheel or rather the body portion of the device to different angular positions. That is, when the body portion is in the position shown by 75 Fig. 4, of the drawings in applicant's former application, the wheel is in its lowermost position in relation thereto. I have provided efficient means whereby the body portion may be lowered, so that it is below the 80 common center of the wheel, thus enabling the operator to adjust one wheel to its lowermost position while the center of the other wheel is above the center position, consequently allowing the device to run upon the 85 regular ground without moving the blade of the plow from its usual substantially vertical position. With this in view, I have provided upon the axle 9 a pivot lever 19, the latter having a handle 20 pivoted thereon as shown at 21, for operating a vertically 90 extending rod 22, carrying a pawl 23. The pawl 23, is clearly shown in engagement with the teeth upon the rack 11, consequently holding the body portion at certain times in 95 rigid relation with the axle and its attachment.

For the purpose of elevating and depressing the stud or crank 13, I have pivoted upon the lever 19, an arm 24 as shown at 100 25, the latter being also connected to the stud as shown at 26. Upon reference to Fig. 4 of the drawings, it will be recognized that the stud is in its lowermost position in relation to the body portion, however, if the 105 lever 19 is moved to a vertical position, it will be recognized that the stud will be raised, consequently lowering the body portion in relation to the wheel.

For the purpose of more readily assuring 110

the efficient operation of the crank, I have provided upon the axle 9, a coil spring 27, one end of which is fast upon the bearing 8, the other end being connected to an adjustable collar 28 as is clearly shown. Further, I have provided a second substantially U-shaped bracket 29, the ends of which are secured to the first mentioned bracket as shown at 30 and 31. It will be recognized, 10 that the bracket 29 connects the ends of the supporting bracket, consequently greatly reinforcing the same, and assuring the durability of the device.

Pivoted upon the body portion 1, as shown 15 at 32, is a substantial bell crank lever 33, one end of the latter being bent at right angles as shown at 34 to form a supporting member 35. This supporting member 35, provides the main supporting structure for 20 the second axle supporting the other wheel. With this in view, I have provided upon the member 35, a depending bracket 36, the latter having connection therewith, through the medium of a pair of spaced apart sleeves 37. 25 The bracket 36 supports, as is clearly shown an axle 38, the latter being received into the hub 39 of the wheel 40. Here a bearing 41 is provided, which is similar in construction to the bearing 16, being secured together as 30 shown at 18.

For normally holding the bracket 36 in a certain position, I have provided thereon a hook 42, which has in engagement therewith one end of a coil spring 43, the other end of 35 the latter being secured to a hook 44, carried upon the member 29, as shown at 45.

A second bell crank lever 46 is provided 40 and pivoted upon the body portion 1, as shown at 47, one of its ends carrying a segmental rack 48, which is fast upon the supporting member 35. A lever 49 is loosely mounted upon the supporting member 35 and has pivotally mounted thereon as shown at 50 a handle 51, the latter having connection with a depending rod 52, which carries 45 a pawl for engagement with the segmental rack 48. Further, this lever is provided with a quadrantal shaped arm 54, the latter being secured thereto as shown at 55, its other end having engagement with the axle 38, as shown at 56. By this arrangement, it 50 will be recognized that as the lever 49 is rocked to different positions, the body portion of the device will be raised and lowered in relation to the wheel 40, thereby serving the purpose hereinbefore set forth.

From the foregoing, it will now be appreciated that the operator, when at his post of duty, upon the device, can easily manipulate the levers 49 and 19 to raise and lower the body portion at opposite sides, thereby providing means, as above described, for holding the plow in its usual substantially vertical position when the device is traveling over irregular ground.

A plow beam 57, is provided, the forward end of which, is secured to a substantially U-shaped bracket 59, carried upon the framework 1, its rear end carrying a plow blade 60. Means have been provided for connection with the plow beam, intermediate its ends, whereby it may be raised and lowered according to the will of the operator. With this in view, I have provided upon the supporting member 35, a bracket 61, over which 75 extends the plow beam, a member 62 being provided upon the bracket for engagement with the plow beam and such means as shown at 63. For the purpose of holding the bracket 61 in different positions, I have 80 provided upon the supporting member 35, a bearing 64, the construction of which, is readily apparent.

The forward extremities of the substantially bell crank levers 33 and 46 respectively, have pivotal connection as shown at 85 65, with pairs of normally downwardly projecting arms 66 and 67. Further bearings 68 are provided upon the framework of the device over which is journaled a bar 69, one 90 end of the latter being bent as shown at 70 to form a downwardly projecting finger for pivotal engagement with the arm 67 as shown at 71.

An adjustable depending lug 72 is provided upon the bar 69, which has pivotal engagement with the arm 66 as shown at 95 73, whereby, when the bar 69 is rotated, the bell crank levers will be rocked simultaneously. For the purpose of holding the bar 100 69 in normal position, a coil spring 74 is provided thereon, one end of which is secured to one of the bearings 68, while its other end is made fast to an adjustable collar 75 on the bar, the collar being held in a normally locked position, in relation thereto, through the medium of a set screw 76.

Upon reference to the drawings, it will be recognized that the bar 69, projects beyond one side of the supporting frame 1. Upon this projecting end, is provided an angularly bent lever 77, the latter having engagement with the bar 69 at an intermediate portion, and being held in rigid relation therewith through the medium of a bearing 115 78. Provided near the extremities of this lever are angularly projecting foot engaging members 79 and 80, the latter serving as a means whereby the operator may manipulate the lever in an efficient manner.

It will now be recognized that when the lever is in the position shown in Fig. 4 of the accompanying drawings, the plow blade is held out of contact with the ground, as the supporting member 35 is in its uppermost position in relation to the body portion. However, it will be recognized that if the lever 77 is operated in such a manner as to rock the bell crank levers 33 and 46 respectively, the plow may be lowered in relation 125 130

to the ground. For normally holding the lever 77 in the position shown in Fig. 4, I have provided thereon a catch 81 pivoted as shown at 82, the catch having a tooth 83 for engagement with a projecting step 84. Means have now been provided for operating the catch so that the operator of the machine may lower the plow when it is desired. With this in view, I have provided 10 upon the lever 77 a pivot foot pedal 85, the latter being secured thereto as shown at 86 and carrying a depending lug 87 for engagement with a downwardly projecting rod 88. Slidably mounted upon the lever 77 through the medium of a bearing 89 is a pawl 90, the latter being held normally in a downward position through the medium of a coil spring 91. The pawl has engagement with the catch 81 by such means as shown at 92 whereby depressed, the catch will be drawn out of engagement with the step 84. The operation of this part of the device is as follows:—The device is in its normal position as shown by Fig. 1 of the accompanying drawings, the plow blade 60 being out of engagement with the ground. If it is desired to lower the blade however, the operator, by use of his foot, manipulates the foot pedal 85, consequently drawing the catch 81 out of engagement with the step 84. When this operation occurs, the upper end of the lever 77 is moved downwardly, consequently manipulating the bell crank levers 33 and 46 respectively, so that the supporting member 35 is lowered, consequently lowering the plow beam and blade. While this operation does not materially affect the raising and lowering of the body portion, the body is slightly raised when the parts 30 are in this position.

As set forth above, I have provided in connection with the plow an efficient means for operating my draft attachment applied to the device to conform with the adjustment 40 of the body portion in relation to the wheel. It will be readily seen that when one side of the body portion is materially higher than the other, the tongue of the vehicle would naturally be higher upon one horse than the other. To obviate this difficulty, and to provide a means for adjusting the tongue, so that it is in relatively the same position to each horse, I have provided the following mechanism: Having one end secured to the 50 extension of the body portion as shown at 93 is a transversely projecting bar 94, the latter being bent as shown at 95 to provide a supporting means for a segmental rack 96, the latter being secured thereto as shown at 97. Further, the end of the bar 94 is bent at right angles to the portion 95 and secured to the frame 1 as shown at 98 and continued on to form the step 84. A pair of tongue supporting members 99 and 100 are provided 60 upon the extension 2 and secured thereto as shown at 101. The upper ends of the supporting members 99 and 100 are spaced apart from each other and have journaled transversely therethrough a pin 102. The pin 102 as is shown pivotally supports a tongue 70 103 as is obvious, and is of the ordinary form. For purpose of connection with one end of a substantially bell crank lever 104 pivoted upon the extension 2 as shown at 105, I have provided the tongue 103 with a 75 slidably projecting finger 106, the latter having connection with the tongue 103 as is shown at 107, and to the bell crank lever as shown at 108. The other end of the bell crank lever has pivoted thereto as shown at 80 109, an arm 110. For the purpose of operating the arm 110, and consequently moving the tongue laterally, I have pivoted upon the said segment 96, as shown at 111 an operating lever 112, the latter having a handle 85 113, pivoted thereon for engagement with a downwardly projecting rod 114, the latter having connection with a pawl 115, which is slidably mounted in a bracket 116, as is clearly shown. For the purpose of normally 90 holding the pawl 115 in engagement with the teeth of the segment 96, I have provided a coil spring 117, which has one end secured to the bracket 116, while its opposite end is secured to the pawl 115 as shown at 118. 95 The arm 110 having connection with the operating lever, assures the positive operation of the tongue during the movement of the lever 112, consequently greatly adding to the efficiency of the device. 100

Provided upon the extension 2 and supported by a lug 119, is a curved arm 120, the latter being engaged within a recess formed in the end of the tongue 103 and whereby the latter is guided in its transverse movement 105 upon the device.

The greatest of stress should be laid upon the simplicity and efficiency of the draft adjusting mechanism inasmuch as it is to be particularly used in connection with a plow 110 of this type, thereby more readily assuring the positive operation of the latter.

Such changes as are permissible by the subjoined claims may be resorted to, if occasion requires, without departing from the spirit and scope of my invention. 115

Having thus fully described my invention, what I claim as new and desire to protect by Letters Patent is:—

1. In a device of the character described, a body portion having an extension formed thereon, a plurality of wheels supporting the said body portion, a plurality of supporting members provided upon the said extension, a tongue pivotally mounted therebetween and having a recess formed therein at the inner end thereof, a curved arm secured to the said extension for engagement with the said recess as a guide means for the said tongue, and an operating lever and coöperating 120 125 130

members as a means for oscillating the said tongue.

2. In a device of the character described, a body portion having an extension formed thereon, a plurality of wheels supporting said body portion, a plurality of supporting members provided upon said extension, a tongue pivotally mounted therebetween and having a recess formed therein at the inner end thereof, a curved arm secured to the said extension for engagement with the said recess as a guide means for the said tongue, a finger projecting from the inner terminal of said tongue, a bell crank lever pivotally mounted upon the said extension and having one end thereof engaging said finger, an arm pivotally engaging the other end of said bell crank lever, a transverse bar connecting the

said body portion with the extension, a segmental rack secured to said transverse bar, 20 an operating lever pivotally mounted upon said segmental rack and engaging the other end of said arm as a means for oscillating the said tongue, a handle pivotally mounted upon said operating lever, a rod connected thereto and a pawl carried by said rod for engagement with said segmental rack for the purpose of substantially holding the said tongue against movement. 25

In testimony whereof I affix my signature in presence of two witnesses.

PAUL EWALD.
